[57] **CLAIM**

The ornamental design for an automobile tire, as shown
and described.

DESCRIPTION

FIG. 1 is a perspective view of an automobile tire showing
our new design, it being understood that the tread
pattern is repeated uniformly throughout the circumfer-
ence of the tire;

FIG. 2 is a front elevation view thereof;

FIG. 3 is a right side elevation view thereof;

FIG. 4 is a left side elevation view thereof;

FIG. 5 is a greatly enlarged fragmentary front elevation
view thereof; and,

FIG. 6 is an enlarged cross-sectional view thereof taken
along line 6—6 in FIG. 5.

FIG.1

FIG.2

FIG. 3

FIG. 4

FIG. 5

FIG. 6
